UNITED STATES PATENT OFFICE.

JETHRO B. CRAWFORD, OF ROCHESTER, NEW YORK.

BOTTLE-STOPPER.

SPECIFICATION forming part of Letters Patent No. 251,838, dated January 3, 1882.

Application filed June 27, 1881. (No model.)

To all whom it may concern:

Be it known that I, JETHRO B. CRAWFORD, of Rochester, Monroe county, New York, have invented a certain new and useful Improvement 5 in Bottle-Stoppers; and I do hereby declare that the following is a full, clear, and exact description of the same, reference being had to the accompanying drawings, in which—

Figure 1 is a sectional elevation of the top 10 of a bottle with my improvement applied thereto. Fig. 2 is an elevation at right angles to Fig. 1. Fig. 3 is a plan of the stopper. Fig. 4 is a detail view, showing the screw, and a cross-section of the coils of wire which engage with 15 the threads thereof.

My improvement relates to that class of bottle-stoppers in which a screw is used for forcing the stopper downward to pack it in its seat.

20 The invention consists in the employment of a screw fast to the stopper-cap, and a bail or yoke having coils formed thereon, which embrace the fixed screw and engage with the threads and form the nut through which the 25 screw moves, thereby avoiding the necessity of a cross-piece with a female thread formed therein, and greatly simplifying and cheapening the device.

In the drawings, A indicates an ordinary 30 beer-bottle. B is the common neck-wire, and C is the bail or yoke, pivoted in the neck-wire, as usual. D is the metallic stopper-cap, and E is a packing ring or disk, of rubber, leather, cork, or any other suitable material. The cap D 35 is formed with a projecting milled edge, a, by which it may be seized and turned with facility. It also has a vertical flange, b, which, when the cap is forced down, overlaps the top edge of the bottle and centers the stopper, also 40 screens or incloses the packing, as shown in Fig. 1. In the bottom of the stopper is formed a cavity or seat, in which rests the packing-disk E, the latter being simply a thin, plain disk, which fits closely to the cap. In the part 45 of the cap which fits directly over the rim of the bottle is a groove, c, which, when the stopper is pressed into place, allows the packing to sink therein, thereby conforming to the shape of the rim and increasing the security of the 50 packing.

G is a short screw, either cast solid with the stopper and made an integral part thereof or formed separately and cast into the stopper,

or otherwise attached so as to form a fixture to the same. It stands up vertically on top, 55 as shown. This screw is threaded with coarse threads, and the bail or yoke C is formed on top with two or more coils, d d, made by bending the wire around a suitable mandrel or form, the coils corresponding in pitch and distance 60 apart with the threads of the screw, and fitting into said threads, and forming the nut through which the screw moves in screwing up and down.

Heredofore thumb-screws have been employed turning downward and forcing the stopper into place. The bearings or nuts through which the screws have passed have been solid and threaded to receive the screws. By coiling the wire bail, as above described, and fitting 70 the coils to the threads of the screw, a good deal of expense is avoided, as the necessity of cutting threads and of using separate cross-pieces connecting the vertical sides of the bail is obviated, while a much more compact and 75 effective device is produced. By making the screw solid with the cap the screw and the cap turn down together and the screw moves readily in the coils.

I do not claim, broadly, the use of a screw 80 to force the stopper down; but

I claim—

1. In a bottle-stopper, the combination of a neck-wire encircling the neck of the bottle, a bail or yoke pivoted to the neck-wire and extending above the bottle, a metallic stopper-cap provided with a packing-disk on its under side, a vertical screw made fast to the top of the stopper-cap, and coils made in the bail or yoke embracing the screw, engaging with the 85 threads thereof, and forming the nut through 90 which the screw moves, as herein shown and described.

2. In a bottle-stopper, the combination of the stopper-cap D, provided with a fixed screw, 95 G, projecting from its top, and a bail or yoke, C, provided with coils d d, which fit the threads of the screw and form the nut through which the screw runs, as herein shown and described.

In witness whereof I have hereunto signed 100 my name in the presence of two subscribing witnesses.

JETHRO B. CRAWFORD.
